(57) **CLAIM**

The ornamental design for a hood of a bag, as shown and described.

DESCRIPTION

FIG. 1 is a front elevational view of one embodiment of a hood of a bag having ears and showing our new design.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is the front elevational view thereof illustrating the hood in an extended position.

FIG. 8 is the rear elevational view thereof illustrating the hood in an extended position.

FIG. 9 is front elevational view of a second embodiment of the hood of a bag showing our new design with ears disclaimed.

FIG. 10 is a rear elevational view thereof.

FIG. 11 is a left side elevational view thereof.

FIG. 12 is a right side elevational view thereof.

FIG. 13 is a top plan view thereof.

FIG. 14 is a bottom plan view thereof.

FIG. 15 is the front elevational view thereof illustrating the hood in an extended position; and,

FIG. 16 is the rear elevational view thereof illustrating the hood in an extended position.

The dotted broken lines in the figure drawings illustrate environment and form no part of the claimed design.
